CLAIM

We claim the ornamental design for an electrical hub, as shown and described.

DESCRIPTION

FIG. 1 is a perspective view of an electrical hub of our new design;
FIG. 2 is a first side view thereof;
FIG. 3 is a second side view thereof;
FIG. 4 is a third side view thereof;
FIG. 5 is a fourth side view thereof;
FIG. 6 is a top view thereof; and,
FIG. 7 is a bottom view thereof.

(Continued)

The broken lines in the drawings are for the purpose of illustrating portions of the electrical hub that form no part of the claimed design.

1 Claim, 6 Drawing Sheets
